UNITED STATES PATENT OFFICE.

HENRY WILLIAMS, OF CHICAGO, ILLINOIS.

IMPROVEMENT IN CORN-HARVESTERS.

Specification forming part of Letters Patent No. 36,046, dated July 29, 1862.

To all whom it may concern:

Be it known that I, HENRY WILLIAMS, of Chicago, in the county of Cook, in the State of Illinois, have invented a new and Improved Mode of Constructing Corn-Harvesters; and I do hereby declare that the following is a full, clear, and exact description of the construction and operation of the same, reference being had to the annexed drawings, and to the letters of reference marked thereon, making a part of this specification, in which—

Figure 1 is a longitudinal section of the corn-harvester through x ; Fig. 2, a plan of the corn-harvester.

The nature of my invention consists, first, of an arrangement allowing at pleasure the dropping of the mowed corn to the ground; second, of the peculiar construction of the whole machine.

To enable others skilled in the art to make and use my invention, I will proceed to describe its construction and operation.

I construct my machine in the following manner: As it consists, first, of its frame; second, of the corn-cutting arrangement; third, of the arrangement carrying the corn after being cut upon the tables, from which it is dropped to the ground; fourth, of the arrangement effecting the dropping of the corn from the gathering-tables to the ground, I shall describe each of these four mentioned subjects separately.

I. *The frame.*—The letters A A represent the main timber of the frame, to which, in right angle and certain distances, the timbers $a a' a'' a'''$ are fastened. The cross-timber B, connecting the side timbers, $b b'$, and which are fastened to the bottom side of the frame-timber A, forms the tongue to my corn-harvester. At the free end of each of the timbers $a a' a'' a'''$ a guide or pedestal, D D' D'' D''', is fastened for the purpose to hang the whole frame, with its connections, upon the shaft E. Around the latter the wheels W W turn. (Fig. 2.)

II. The corn mowing or cutting arrangement consists of the knives or sickles Q Q', (seen in front of the frame-timber A and to each side of the tongue B.) The two sickles are guided by means of the guides G G G G (seen at one side of the tongue B) and G' G' G' G', (seen at the other side of the tongue,) parallel to the frame-timber A. The guides G and G' are fastened in front to the frame-timber A. The

shaft M M (seen in the center between the two inner frame-timbers, $a' a''$, and parallel to them) is held in its place by means of the pedestal or journal-box Z (the latter is fastened to the top side of the timber A) on one side, and by the pedestal N N on the opposite side or end. The pedestal N N is fastened to the upper side of the frame-timber a'' . Near or close to the pedestal N the cog-wheel J is fastened to shaft M. At the opposite end the gear-wheel h is attached. The cog-wheel J communicates motion directly to shaft M, upon which it is fastened, as soon as the large cog-wheel H (H is fastened to the wheel-shaft E) receives motion by means of moving the machine in forward or backward direction. So, also, motion is transmitted to the tooth-wheel h, for the purpose to revolve the smaller tooth-wheels i i' with their plates m m', Fig. 2. To each of the plates m m' a crank-pin, w w', is fastened, (their position to each other is ninety degrees,) which communicates motion, by means of the coupling-rods q q', to the sickles Q Q'. At the ends of the wheel-shaft E the ratchet-wheels R R', with their pawls or stops S S', are seen. (Fig. 2.) The ratchet-wheels are fastened to the shaft E, while their pawls j j' are attached to the inside of the hub-rim of the wheels w w'. The object of said ratchet-wheels and their corresponding pawls (the latter, as already mentioned, are fastened to the wheel-hubs) is to communicate the motion of the wheels W W' to shaft E and its connection, when the whole machine is moved in forward direction. In moving the machine forward the wheels W W' will follow in the same direction, so, also, the pawls j j', which causes the latter to catch the teeth of the ratchet-wheels R R', forcing thereby the shaft E, with its connections, to move, also, in the same direction. Moving the machine backward, no connection in relation of transmitting motion is formed or better effected between the wheels W W' and the shaft E. The relative position of the ratchet-wheels and their pawls to each other, Fig. 1, explains it. With reference to the above mentioned, the mowing or cutting of the corn is effected by moving the frame of the machine in forward direction, which causes (in consequence of the connection formed between the frame and the wheel-shaft E by means of the pedestals or journal-boxes D D' D'' D''') and the ratch-

et-wheel arrangement) the forward motion of the cog-wheel H. Cog-wheel J, being in direct connection with H, communicates motion to shaft M, the latter to wheel h, h to i' m', and i m, and m m', by means of the crank-pins w w' and the coupling-rods q q', to the sickles Q Q'. The motion given to the sickles Q Q' is a horizontally forward and backward one. The forward motion of the whole machine, in connection with the action of the sickles Q Q', causes the moving or cutting of the corn.

III. The arrangement for carrying the corn after being cut upon the tables, from which it is dropped to the ground, consists of two vertical shafts, I I I I', which are placed in equal distance from the center line drawn through the machine, Fig. 2, upon the frame-timber A. The same are held in their vertical position by means of the flat brace L L. The same extends parallel to the frame-timber A and above it from shaft I I to shaft I I'. At their upper end they are furnished with the arms or fingers 1 1, 2 2, 1' 1', 2' 2'. To their lower end the grooved pulleys Y Y' are fastened—that is to say, Y is attached to shaft I I, Y' to shaft I I'. The position of said pulleys is at the lower end of the shafts I I, I I', and between the frame-timber A and the flat brace L L. The latter is fastened to frame-timber A by means of the two angle-irons 5 5, which are placed close to the inner sides of the shafts I I I I'. The pulley Y', fastened upon shaft X, communicates motion to pulley Y and shaft I I by means of belt y. Pulley Y'', (see Fig. 1,) being also fastened to shaft X, but below Y', transmits motion to pulley Y'' and shaft I I'. The revolving shafts I I I I', with their fingers, (called together "reels,") have the object to bring the corn before or to the sickles Q Q', and after being cut to throw the same, in connection with the converging bended track-clearers n n and n' n', upon the platforms or tables P P'. The track-clearers n n n' n' are fastened upon the frame-timber A at each end of it. (See Fig. 2.) Close to the inside of the frame-timber A the cog-wheel K, with its notched hub V', is fastened to the shaft M, communicating directly with the cog-wheel K', Fig. 1. The latter is attached to the vertical shaft X, so, also, the pulleys Y' Y''. Shaft X is held in its position by means of passing with its upper end through the flat brace L L, and extending with its lower end somewhat into the pedestal or journal-box Z of shaft M. (Z is seen on the top of the frame-timber A.) Between the frame-timbers a, a', a'', and a''', I place a table or platform, P P', Fig. 2. Each one of them is formed by laying a piece of cloth or any other suitable material around the rollers r r' (the latter are extended from a to a' and from a'' to a''', and placed parallel to each other and to the frame-timber A) in shape of an endless belt. In line with the frame-timbers a a' a'' a''', I place the shafts F F' F'' F''', with their corresponding fingers. The shafts F F'' are stationary, and therefore fastened to the top of the frame-timbers a a''. The position of the fingers f f' f'' of shaft F

and the fingers f''' f'''' f''''' of shaft F''' is a declined one. The shafts F' F'', with their straight fingers, are calculated to revolve. Each one of them is guided by means of two boxes or guides—F' by the guides t and t', F'' by t'' and t''. These guides are placed near to the lower end of the shafts F' F''. The guides t and t''' are fastened to the top side of the frame-timber A, t' and t'' upon the frame-timbers a' and a''. The shafts F F' and their corresponding fingers form an extension of the platforms P and P'. The operation to carry the corn after being cut upon the tables P P', and their revolving extensions, is as follows: In the moment the machine is moved forward shaft E turns, and with its cog-wheel H H transmits the motion to the cog-wheels J and K. Both J and K are fastened upon shaft M.) K, as in direct contact with cog-wheel K', communicates motion to K' and to the pulleys Y''' Y'. the latter transfer their motion by means of The belts y y' to the pulleys Y and Y', the shafts I I I I', (to which Y and Y' are fastened.) This causes the shafts I I I I' and their fingers to revolve in the direction the arrows, Fig. 2, indicate, in consequence of which the mowed corn is carried toward the platforms P P'. The peculiar shape and the position of the track-clearers n n and n' n', so, also, the sheet-iron plates d d' d'' d''', which form sides to the tables P P', are calculated to assist in effecting the carrying of the mowed corn upon the tables P P' and their extensions.

IV. The arrangement to effect at pleasure the dropping of the mowed corn resting upon the tables P P' to the ground consists of the grooved pulleys O O' O'' O'''. The double pulley O O' (containing a notched hub T') is placed loose fitting upon shaft M. Its purpose is to transmit motion to the revolving-table parts F' F'' by means of the belts y'' y''. The latter transmit motion to the pulleys O''' (O'' containing a notched hub, v'') and O'', (O' containing the notched hub v'.) Both pulleys are fastened to their corresponding shaft—that is, O''' to F' and O'' to F''. Upon each of the revolving shafts I place a notched hub, (fitting its corresponding shaft loosely,) which I connect by means of the rod v v v. (The latter is again in connection with the ring g g, see Fig. 1, which surrounds the hub of the pulley O.) The notched hub T (T fitting the notched hub O'' of pulley O''') fits loose shaft F'', while the notched hub T''' (T''' fitting the notched hub v' of the pulley O'') is placed upon shaft F''. The position of the pulleys O''' O'' and their corresponding notched hubs, T T'', is between the guides of the revolving shafts F F'', t t', and t'' t''. To the inner side of the frame-timber A, I fasten the two springs p p'. Their object is to press the notched hubs T T'' against their corresponding pulleys—T against O''' and T'' against O''.

The operation of the dropping arrangement is as follows: The machine is in forward motion. Cog-wheel H revolves shaft M by means of cog-wheel J, and with it cog-wheel

K and its notched hub v' . Suppose the operator of the machine wishes to drop the corn from the tables P P' to the ground, then he will push the rod $v v v$, at the point where said rod is in connection with the ring $g g$, by his foot (Fig. 1) toward the frame-timber A, which causes the double pulley O O' to catch the notched hub v' of cog-wheel K by means of notched hub T of the pulley O O', in consequence of which the double pulley O O' becomes revolved in the direction the shaft M turns. It also causes the depression of the springs $p p'$ and the disconnection between the notched hubs T'' and their corresponding pulleys, O'' O''. As soon as the double pulley O O' becomes revolved motion is immediately transmitted (by means of the belts $y'' y'''$) to the pulleys O'' O''' and their corresponding shafts, F' F'', which causes a toward motion of the fingers $g g' g''$ (of shaft F') and $h h' h''$, (of shaft F''), by which the dropping of the corn from both tables P P' at once is effected. In the moment the operator withdraws his foot from the rod $v v$ the springs $p p'$ take their natural position, which causes the disconnection between the double

pulley O O' and the shaft M. The notched hub T is drawn back and out of the notch v' , and the tables P P' remain again in their position to receive the corn.

The letter C represents the seat for the operator of the machine. The same rests upon two iron rods, which are fastened to the frame-timber A.

What I claim as my invention, and desire to secure by Letters Patent, is—

1. The revolving tables consisting of the shafts F F' F'' F''', in combination with the arrangement by which the revolving motion or the stopping of the revolving shafts F' F'' at the pleasure of the driver can be effected, substantially as described.

2. Operating the sickles Q Q and the revolving shafts F F'' by means of connecting-shaft E with shaft M, and M with F' F'', in the manner as set forth.

HENRY WILLIAMS.
